(57) **CLAIM**

I claim the ornamental design for a planter, as shown and described.

DESCRIPTION

FIG. 1 is a top right front side perspective view of a planter, showing my new design;

FIG. 2 is a bottom right rear side perspective view thereof;

FIG. 3 is a front side elevation view thereof;

FIG. 4 is a rear side elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-section view along line 9-9 in FIG. 1; and,

FIG. 10 is a cross-section view along line 10-10 in FIG. 1.

The broken lines depict portions of the planter and form no part of the claimed design.

1 Claim, 9 Drawing Sheets
